US00D465497S

(12) **United States Design Patent** (10) Patent No.: **US D465,497 S**
(45) Date of Patent: **** Nov. 12, 2002**

(54) **USER INTERFACE COMPONENT FOR A DISPLAY**

(75) Inventors: **Chien-sen Weng**, Taipei (TW);
Hsiang-tsun Yen, Taipei (TW)

(73) Assignee: **Acer Digital Services, Corp.** (TW)

(**) Term: **14 Years**

(21) Appl. No.: **29/130,802**

(22) Filed: **Oct. 10, 2000**

(51) LOC (7) Cl. **14-02**

(52) U.S. Cl. **D14/485**

(58) Field of Search **D14/485-95, 474, D14/478-80; D18/24-33; D19/6, 9, 10; D20/11; D21/324-33; 345/326, 339-58; 360/133, 135, 97.01-99.12; 395/186; 369/272-3, 282-8, 280, 291**

(57) **CLAIM**

The ornamental design for a user interface component for a display, as shown and described.

DESCRIPTION

The single FIGURE is a front view of a user interface component for a display of the present invention, the broken line drawing of a display is for illustrative purposes only and forms no part of the claimed design.

Phantom lining, where utilized, is for illustrative purposes only and is not intended to limit the claimed design to the features shown in phantom.
